UNITED STATES PATENT OFFICE.

JAMES FRANKLIN BROWN, OF CINCINNATI, OHIO.

DESIGN FOR A STORE FRONT.

Application filed March 12, 1928. Serial No. 25,806. Term of patent 14 years.

To all whom it may concern:

Be it known that I, JAMES FRANKLIN BROWN, a citizen of the United States, residing in Cincinnati, in the county of Hamilton and State of Ohio, have invented a new, original, and ornamental Design for a Store Front, of which the following is a specification, reference being had to the accompanying drawing, forming part thereof, in which—

Fig. 1 is a front elevation of a store front, showing my design; and,

Fig. 2 is a side elevation of the same.

I claim:

The ornamental design for a store front, substantially as shown.

JAMES FRANKLIN BROWN.
